CLAIM

The ornamental design for ultrasonic cleaner, as shown and described.

DESCRIPTION

FIG. 1 is a front elevational view of an ultrasonic cleaner showing my new design;

FIG. 2 is a rear elevational view thereof;

FIG. 3 is a left side view thereof;

FIG. 4 is a right side view thereof;

FIG. 5 is a top plan view thereof; and,

FIG. 6 is a bottom plan view thereof.

The broken lines shown form no part of the claimed design. The front details as shown in FIG. 1 are flush with the surface.
